IMPROVEMENT IN TAP BORERS.

SILAS S. CROCKER, OF MAQUOKETA, IOWA, ASSIGNOR TO HIMSELF AND
D. R. CROCKER, OF SAME PLACE.

Letters Patent No. 60,342, dated December 11, 1866.

The Schedule referred to in these Letters Patent and making part of the same.

TO ALL WHOM IT MAY CONCERN:

Be it known that I, SILAS S. CROCKER, of Maquoketa, in the county of Jackson, and State of Iowa, have invented a new and Improved Tap or Hub Borer; and I do hereby declare the following to be a full, clear, and exact description of the same, sufficient to enable one skilled in the art, to which the invention appertains to make use of it, reference being had to the accompanying drawings, which form a part of this specification, and in which my invention is represented by a perspective view.

The improvement consists of a volute-shaped tool formed of a single curved plate, whose salient edge is sharpened for the purpose of reaming out a conical hole, such as that in a hub for the reception of the box, a bung or tap hole, or that in a faucet for the reception of a spigot.

In the drawings A is the handle and B the shank of the tool; C is the blade, which is formed into a volute shape, one edge *c* projecting out further than the other, *d*, the space between forming a throat, through which the shaving cut by the edge *c* will pass. The screw point of the tool is used for boring into the solid wood as in tapping barrels, but is not necessary in boring hubs.

Having described my invention, what I claim therein as new, and desire to secure by Letters Patent, is—

The volute-shaped tool with a sharpened, salient spiral edge with the gimblet point, substantially as described.

S. S. CROCKER.
